(57) **CLAIM**

The ornamental design for a bag, as shown and described.

DESCRIPTION

FIG. 1 is a front view of a bag showing our new design;
FIG. 2 is a right side view, the left side view being a mirror
image thereof;

FIG. 3 is a top view thereof;

FIG. 4 is a bottom view thereof;

FIG. 5 is a cross-sectional view along line 5—5 of FIG. 2;

FIG. 6 is a perspective view of the bag shown in FIG. 1 when
the bag is in a filled condition; and,

FIG. 7 is a perspective view of the bag shown in FIG. 6 when
it is in use hanging from a support.

The broken line showing of a support is included for the
purpose of illustrating environmental structure and forms no
part of the claimed design.
